UNITED STATES PATENT OFFICE.

WILLIAM TAYLOR DICKEY, OF PORTSMOUTH, VIRGINIA, ASSIGNOR TO AMERICAN CONCRETE TIE CORPORATION, OF PORTSMOUTH, VIRGINIA.

CONCRETE TIE AND RAIL CLAMP.

Application filed September 7, 1922. Serial No. 526,697.

To all whom it may concern:

Be it known that I, WILLIAM T. DICKEY, a citizen of the United States, residing at Portsmouth, in the county of Norfolk and State of Virginia, have invented a new and useful Concrete Tie and Rail Clamp, of which the following is a specification.

This invention relates to concrete ties and clamps for securing a rail thereto.

10 The object of the invention is to provide a concrete tie reinforced so as to resist strains to which it may be subjected and equipped with rail clamps constructed so as to prevent all possibility of chipping of 15 the tie by the strain from the rails, and which permit the rail to have a slight vertical movement.

With the foregoing and other objects in view which will appear as the description 20 proceeds, the invention resides in the combination and arrangement of parts and in the details of construction hereinafter described and claimed, it being understood that changes in the precise embodiment of the 25 invention herein disclosed, may be made within the scope of what is claimed without departing from the spirit of the invention.

In the accompanying drawings:—

Figure 1 represents a plan view of a tie 30 constructed in accordance with this invention with two rails shown applied thereto and secured by the clamp constituting a part of the invention.

Fig. 2 is a side elevation of the tie with 35 the rails shown in cross section.

Fig. 3 is an enlarged detail vertical section taken on the line 3—3 of Fig. 2.

Fig. 4 is a plan view of one of the clamps constituting a part of the invention, and

40 Fig. 5 is a longitudinal section taken on the line 5—5 of Fig. 4.

In the embodiment illustrated, the tie 1 which constitutes a part of this invention is construction of concrete, being preferably 45 of the cross sectional contour shown in Fig. 3, and is reinforced by a sheet 2 of expanded metal which extends the full length of the tie about one inch more or less beneath the top surface thereof. The $\frac{3}{4}$ " bars 3 and 50 4 extend the full length of the tie and another $\frac{3}{4}$ " bar 5 about four feet long is arranged between them, the three being located in the upper portion of the tie just under the expanded metal plate 2 as is shown 55 clearly in Fig. 3. Located in the lower por-

tion of the tie one inch from the bottom and extending the full length thereof are two reinforcing bars 6 and 7 of about three quarters of an inch in diameter, more or less.

Two additional reinforced bars 8 and 9 about 18 inches long are arranged beneath the rail R. Expanded metal plate 10 is also embedded in the tie in a plane one inch from the bottom and below the bars 6, 7, 8 and 9 which extend under the rail. The longitudinal lower edges of the tie 1 are preferably rounded as shown at 1^a to facilitate tamping. These rounded edges, as shown at 1^a, also act as a brace to hold the tie in an upright position.

The tie 1 is provided adjacent the bottom thereof in its opposite side edges with recesses 11 to facilitate the application of the nuts 12 which are engaged with the lower ends of the bolts 13. These bolts are provided at their upper ends with nuts 13^a which secure the rail clamping plates 15, a coiled spring 14 being arranged between the nuts 13^a and said plates. The nuts on the lower ends of the bolts corrode after they have been in use some time and are difficult to remove. The nuts on the upper ends may easily be taken off and permit the clamps to be removed in a few seconds.

The clamping plates 15 are each constructed as shown in detail in Figs. 4 and 5, being mounted for vertical movement on the bolts 13 which pass through longitudinally extending slots 16 in the fasteners or plates. 90 Each of these clamping plates includes a finger 17 which overhangs and engages the base flange of the rail R. Each of the fasteners 15 is provided with a longitudinal slot 16 and the remote ends of the fasteners are extended at right angles as is shown at 18, being designed to enter sockets 19 formed in the upper faces of the tie 1 on opposite sides of the rails. The toes or ends 18 of the clamp are beveled on their outer faces and result in distributing the strain or pressure of the clamp vertically downward and at the body of the tie at an angle instead of exerting a straight back push and thus prevents the clamp chipping off the concrete under the strain exerted thereon by the rails.

The springs 14 not only absorb the upward shock from the wave motion of the rail, but they also act as nut locks for the nuts on the bolts.

- The rails R are preferably mounted on cushioning plates 22 and are held engaged therewith by the clamps 15. These clamps 15 may be moved toward and away from each other owing to the formation of the slots 16 therein, the object of this being to permit the clamps to be shifted to provide for the adjustment of the rail and proper mounting of the clamps.
10. The tie 1 herein disclosed is practically indestructible and the cost thereof is nominal probably not exceeding that of a first class wooden tie, while its life greatly exceeds that of such a tie.
15. The fasteners 15 are so constructed and mounted that they will grip and hold the rail and yet permit a slight vertical movement thereof. It will also be observed that the bolts and fasteners can be inserted and 20 removed without disturbing the position of the tie in the ballast or jacking up the track. If the rail wears down in the tie, the fasteners 15 will follow the rail and hold it securely owing to the presence of the springs.
25. 14. It is of course understood that the fasteners 15 may be applied to any kind of a tie whether made of metal or concrete or any other material.
- I claim:—
30. 1. A cement railroad tie having bolt receiving openings therein and sockets adjacent said openings, rail clamps mounted on said bolts and having toes to enter said sockets, said toes being beveled on their outer faces at their terminals to exert pressure at an oblique angle on the tie.
35. 2. A railroad clamping plate having a

longitudinally extending bolt receiving slot therein with a rail engaging finger at one end and a tie engaging toe at the other, said toe extending at right angles to the body of the clamp and having its rear face beveled to exert pressure at an oblique angle on the tie and prevent chipping of the tie.

3. A cement railroad tie having bolt receiving openings therein and sockets adjacent said openings, bolts mounted in said openings, rail clamps mounted on said bolts and having toes to enter said sockets, said toes being beveled on their outer faces at their terminals to exert pressure at an oblique angle on the tie, and springs on said bolts above said clamps and an adjustable member on the bolt and cooperating with the spring.

4. A cement railroad tie having bolt receiving openings therein and sockets adjacent said openings, bolts mounted in said openings, rail clamps mounted on said bolts, and having toes to enter said sockets, said toes being beveled on their outer faces at their terminals to exert pressure at an oblique angle on the tie, springs on said bolts above said clamps and cooperating with the spring; said bolts having removable nuts on their opposite ends.

In testimony that I claim the foregoing as my own, I have hereto affixed my signature in the presence of two witnesses.

WILLIAM TAYLOR DICKEY.
